HAIRCUTTING CLOTH OR APRON

Fred H. Richmond, St. Louis, Mo.

Application March 13, 1947, Serial No. 734,466

3 Claims. (Cl. 2—50)

1

The present invention relates to certain new and useful improvements in hair cutting cloths or aprons, and more particularly to improvements upon my prior patent numbered 2,123,436, dated July 12, 1938.

These cloths are used by barbers for preventing hair clippings and dandruff from falling upon the clothes of their customers. The principal object of the present invention is to provide a generally rectangular shield, cloth or apron for positioning over the shoulders and around the neck of the customer, for catching such hair droppings, the said cloth being formed with a V-shaped opening extended downward through its upper end or side and adapted to embrace the neck of the customer, the margins of the V-shaped opening being hemmed over inserts of elastic cords or tapes that are stretched or tensioned in the process of making the cloth, in such manner as to normally form and maintain pockers or wrinkles in the hems or at the lower portions of these hems, whereby the parted sides of the cloth may be snugly stretched under tension around the neck of the customer, regardless of the size or bulk of the neck, and there releasably secured in position by means of a suitable fastening device.

Another object of the invention is to provide in a barber's cloth or apron of the kind referred to, a special form of fastening device for releasably securing the cloth in place about the neck of the customer, without the necessity of pinning, puncturing or injuring the hem of the cloth or the elastic cord or tape as enclosed therein.

With the stated objects in view, together with such other objects and advantages as may appear from the following specification, attention is directed to the accompanying drawing as exemplifying a preferred embodiment of the invention, and wherein:

Figure 1 is a plan view of a barber's cloth as formed in accordance with this invention.

Figure 2 is a similar plan view of the cloth, showing the lower or inner end of the V-shaped opening or parting thereof as spread apart laterally at its margins and rounded semi-circularly at each side for embracing the neck of a customer, this formation being brought about of course in the act of placing the cloth upon the customer.

Figure 3 is a perspective view of the cloth showing its formation as drawn up around the neck of a customer, and releasably secured to position by means of the special form of fasten-

2

ing device as contemplated and provided in this invention.

Figure 4 is a section on the line 4—4 of Figure 3, showing on a greatly enlarged scale, the construction and mode of operation of the special form of fastening device.

Figure 5 is a perspective view similar to that of Figure 3, showing however the cloth as secured to position by means of a common pin, in lieu of the special fastening device shown in Figure 3.

In practising this invention, I provide a flexible cloth of any suitable kind of material, preferably rectangular in form and here represented generally at 5. A V-shaped opening or parting 6 is cut down medially through the upper side of the cloth, as shown in Figures 1 and 2. The cloth is hemmed upon all margins as indicated at 7, but within the hemmed margins 7a of the V-shaped parting 6 there is enclosed a length of elastic tape 8 which is folded medially upon itself to form the lower crotch 8a of the V-shaped opening 6. In the process of mounting this tape 8 within the hems 7a, the tape is stretched substantially upward from the lower crotch 8a, as it is sewn and hemmed in place, and so that when the hems are completed and released the contractive pull of the tapes will cause the hems to pucker and wrinkle as indicated at 9, at the lower portion of the V-shaped parting 6. A buttonhole 10 is formed medially through one of the hems 7a at one side of the parting 6, for a purpose later explained.

For use with the cloth as described a special form of fastening device 11 is provided, the same comprising a pair of finger pieces 12, 13, pivotally connected by a pin 13a passed transversely through tabs 14 turned down from the upper finger piece 12. These finger pieces are normally urged resiliently together by a coil spring 15 seated over the pin 13a and braced at its ends against the pieces 12, 13. A button 16 formed with a central socket 16a is anchored at 16b to the inner face of the upper finger piece 12, and a complementary obtuse spur 17 is similarly anchored at 17b to the inner face of the other finger piece 13, in alignment with and adapted to enter the socket 16a of the finger piece 12 as the pair of finger pieces close together. As shown in Figure 4, this fastening device 11 may be mounted at the button hole 10 in one of the hems 7a of the cloth 5, by passing the button 16 through the button-hole to place the shank of the button 16 within the hole. The opposite hem 7a of the cloth may then be

drawn between the opened finger piece 12, 13, within the button 16 and spur 17 on opposite sides of such hem, and as the finger pieces are released and automatically close together the spur 17 engages and forces the hem with the spur into the socket 16a, thus firmly securing the cloth to its desired position.

The form of cloth or apron as here provided has no permanently attached buttons or fastenings to interfere with laundering. The button hole 10 affords a handy place for securing the fastening device 11 against misplacement when the latter is not in use. In use this fastening element need not necessarily be inserted in the button hole 10, but may be used independently of the button hole, for pinching the sides of the apron together at any desired point.

Any desired kind or form of elastic material may be employed in the making of this hair cutting cloth or apron, such as elastic cord, tape or strips of webbing, or any other stretchable material, and if desired the cloth may be made of double layers, with such elastic material sewn in between the layers at the margins of the V-shaped neck opening.

In use, the cloth is positioned upon the chest and shoulders of the customer, as indicated in Figure 2. The parted sides of the cloth are then drawn up resiliently around and back of the neck and the overlapped sides are finally secured together by means of the fastening device 11, in manner already pointed out. If preferred, a common pin 18 may be employed for securing the cloth in place, in lieu of the fastening device 11, as shown in Figure 5. From the construction as shown, it is obvious that this form of barber's cloth is adapted for snugly and yieldingly fitting around necks of varying size, including children and adults, and is well adapted for preventing hair clippings from working down between the cloth and the neck of the customer, and onto his clothes.

The forming of the parting opening as of V-shape and the particular manner in which the edges are tensioned provides several definite advantages. With the elastic element 8 extending on both side edges of the parting and shaped relative to the crotch of the opening and secured to the crotch, thus placing the medial zone of the elastic as anchored to the point or crotch zone of the V-opening, such zone becomes stabilized and definitely shaped, enabling the remainder of the elastic to be properly tensioned during the formation of the covering for the elastic provided by the hem, with the elastic ends secured to the hem while under tension. The definite shape of the crotch zone thus produced is not disadvantageous since this underlies the chin of the customer when the cloth is applied. Hence, both sides of the lower zone of the parting edges are of similar tensioned characteristics and provide similar puckers and/or wrinkles on both sides of such zones, the latter zones having a length such as to include the front and the forward portion of the sides of the neck. The puckered zone will readily conform to the neck, as will the untensioned portions of the hem, as the cloth is applied, there being a close fit about the neck except within the crotch zone, the latter exerting no pressure at the medial front of the neck, thus avoiding discomfort to the customer at this portion of the neck such, for instance, as to force swallowing actions and the like. The remainder may then be closely fitting.

The structure of the securing means shown in Fig. 4 is above set forth. It presents a number of advantageous conditions. For instance, it can be used either with or without the button-hole 10, the latter serving to actually position the location of the means in service, and to carry the means to prevent loss when the cloth is not in service. However, as above explained, the means can be used without the button-hole, this being due to the fact that in closing the means upon the positioned rear portions of the cloth the stud 17 does not penetrate the material but simply moves it into the flared opening of the button 16. Whether the material thus inserted is of one or two plies, the stud serves to hold the inserted portion or portions in position by tending to clamp the material between it and the button and at the same time produce a pseudo curvature to the material inserted, such as will prevent its being withdrawn other than by opening the means. Since there is no perforating of the material, the cloth is not damaged by the application of the means. Obviously, by removing the means from the cloth, the latter is freed from all projecting structure. The button-hole when used provides no difficulty in this respect, the result being that the hair cloth can be easily laundered without danger of damage. When the button-hole is used with the securing means it is located external of the shank of the button and its walls do not enter between the stud and the flared wall of the button opening.

And while I have here shown and described a specific embodiment of the invention, and specific structural features thereof, it is to be understood that the features as shown may be changed or modified as desired, within the scope of the claims.

I claim:

1. In hair cutting cloth assemblages, wherein the neck-enclosing zone is tensionable, an assemblage of such type characterized in that the neck-applied zone of the cloth includes a medial V-shaped parting having its edges of double-ply formation and with the lower zone of each edge carrying the tensioning means, said means comprising an elongated elastic element mounted between the parting edge plies and extending into the opposite side edges of the parting, a medial portion of the element being folded into conformity with the crotch of the parting and being secured to the cloth at such crotch, said element having a length less than the peripheral length of the parting and being additionally secured to and within the cloth plies beyond the element mid-zone while the unsecured zones of the element are under tension to thereby produce a cloth having the tensioned zone of the plies and adjacent body normally puckered and/or wrinkled to provide a zone shapeable about the forward and side portions of the neck with the untensioned edges of the parting forming the covering for the rear portion of the neck by cloth overlapping, and means carried by the untensioned ply zones for temporarily securing the cloth in its active service position about the neck of the customer.

2. An assemblage as in claim 1 characterized in that the medial portion of the element is folded upon itself within the crotch zone prior to being secured to the crotch, such securing serving to anchor the element in the crotch zone in conformity with the pointed crotch zone of the parting to provide a definitely-shaped medial zone for positioning at the front of the neck and

underlying the chin of the customer, whereby the tensioned portions beyond the crotch are conformable to the front and forward side zones of the neck with the untensioned zones of the parting conformable about the remainder of the sides and the rear of the neck.

3. An assemblage as in claim 1 characterized in that one of the untensioned ply zones of the edges of the parting is formed with a single button-hole usable to removably support the temporary securing means during both active and inactive service periods of the assemblage, removal of the securing means from the button-hole and thereby freeing the means from the apron rendering the cloth free for washing and with the cloth completely flexible for washing purposes.
